UNITED STATES PATENT OFFICE

2,365,818

MARINE LEG UNLOADING APPARATUS

Homer K. Herrick, South Pasadena, and Charles J. Horn, Arcadia, Calif., assignors to Stephens-Adamson Mfg. Co., a corporation of Illinois

Application November 27, 1942, Serial No. 467,128

11 Claims. (Cl. 198—88)

The principal object of this invention is to provide a marine leg unloading apparatus that will give the boat or pickup end of the elevator leg a great range of positions to meet the varied conditions of water level and depth of lading as well as the width of the ship to be unloaded and will also fold into a safe storage position within clearance lines and low head space.

Further objects and advantages of the invention will appear as the disclosure proceeds and the description is read in connection with the accompanying drawings in which

Fig. 1 is a diagrammatic elevation showing the apparatus in solid lines in one position it may assume in unloading a ship and in dotted lines another position it may assume when stowed out of use;

Fig. 2 is a similar diagram showing the boom depressed 22° below the horizontal with the marine leg at its innermost position in solid lines and at its outermost position in dotted lines;

Fig. 3 is a similar diagram showing the boom raised 25° above the horizontal with the marine leg at its outermost position in solid lines and at its innermost position in dotted lines;

Fig. 4 is a similar diagram showing the boom raised 80° above the horizontal and the leg at its most extended position;

Figs. 5 and 6 are diagrammatic plan views of the top and bottom chords, respectively, of the forked boom;

Fig. 7 is an enlarged view of a portion of the apparatus in the position shown in solid lines in Fig. 1;

Fig. 8 is a similar view of a fragment of that apparatus in the position the parts assume when the leg is brought to its innermost position while the boom is horizontal;

Fig. 9 is an elevation of the apparatus shown in Fig. 7 looking at it from the left with the belt conveyor omitted;

Fig. 10 is an enlarged fragment showing the mounting for the elevator leg and an associated belt conveyor on the boom;

Fig. 11 is a horizontal section taken on the line 11—11 of Fig. 10;

Fig. 12 is a vertical section taken on the line 12—12 of Fig. 11;

Fig. 13 is a fragment adjacent to the trunnions of the boom, in vertical section, showing the weatherproof spout construction by which sugar is delivered from the conveyor apparatus on the boom to conveyor apparatus on the tower frame;

Figs. 14, 15 and 16 are diagrammatic vertical

sections showing the spout in three selected positions, corresponding to the solid line positions in Figs. 2 and 3, and to the dotted line position in Fig. 1, and

Fig. 17 is a transverse section on the line 17—17 of Fig. 13.

But these specific drawings and the corresponding description are used for the purpose of disclosure only and are not intended to impose unnecessary limitations on the claims.

General description

In Fig. 1 a familiar form of marine leg bucket elevator 10 is shown in vertical position extending through the hatch 11 into the hold of a ship 12, lying along side a wharf 13 having a clearance line indicated in dot and dash line 14.

The marine leg is suspended on a horizontal shaft 15 mounted to move in and out along a forked boom 16 pivoted on trunnions 17 to swing up and down between the positions shown in Figs. 2 and 4.

The trunnions 17 are journaled in bearings 18 on a tower frame 19 mounted on a truck 20 to travel along a track 21 on the wharf 13.

The elevator leg picks up the lading, in this instance granulated sugar, at the boot 22 and delivers to a telescoping chute 23 which, in turn, delivers to a belt conveyor 24 on the boom movable in and out with the elevator leg and delivering to a second belt conveyor 25 on the boom, delivering to a spout 26 that delivers to a third belt conveyor 27 on the tower frame 19 that delivers to a take-away belt conveyor 28 under a shed 29 and leading to a storage warehouse.

The hoisting machinery for hoisting and controlling the boom is arranged on a floor, generally indicated by 30 (Figs. 1 and 7) and is illustrated diagrammatically here by a motor driven drum 31. The motor is controlled by the Ward-Leonard system and there are suitable limit switches for stopping the boom in its extreme positions.

A compensating counterweight system 32 with backhaul ropes or cables 33, cooperates with the hoisting machinery to limit the work to be done in the most extended positions of the apparatus and to provide safety in the elevated and stowed positions as well as to assist in lowering the boom from elevated or stowed position against an off shore wind.

The tower frame

The tower frame 19 is shown as fabricated from structural steel and its construction and design will be sufficiently understood by engi-

neers from the more or less diagrammatic views without specific description and illustration.

The truck for supporting the apparatus and distributing the load to the rails on the wharf irrespective of unevennesses is fully disclosed in a copending application, Serial Number 467,129, filed of even date herewith.

The boom

The boom is also fabricated of structural steel and its frame construction will be sufficiently understood from the plans in Figs. 5 and 6 and the elevations in Figs. 1, 4 and 7. The top chord, shown in plan in Fig. 5, is split to the cross brace 34 to provide clearance for the marine leg in the extreme lower position of the boom, shown in Fig. 2. The bottom chord, shown in plan in Fig. 6, is split to the cross brace 35 to provide clearance for the marine leg in the stowed position, shown in dotted lines in Fig. 1.

The two chords are interconnected into a cantilever beam structure by the struts and braces 36 and 37. At the rear, or to the left in Figs. 1, 2, 3 and 7, the boom is also forked and comprises two curved arms 38 stiffened by braces 39 (Fig. 9) and providing drum surfaces 40, 41 and 42.

The drum surfaces 41 receive cables 43, co-operating with the drum 31 to hoist the boom.

The compensating counterweight and backhaul rope system

In one embodiment of the apparatus that has proved successful the trunnions 17 are more than 46 feet above the surface of the rails 21 on the wharf and from the trunnions 17 to the horizontal shaft 15, from which the marine leg is swung, is in excess of 63 feet. From this it will be obvious that the structure in stowed position is comparable to the height of a twelve story building and is subject to enormous wind stresses in addition to those imposed by the weight of the structure itself and the tonnage during operation. The operator must have certain control of the boom throughout the entire range of the up and down movement regardless of the direction and intensity of the wind. And, in addition, the overhanging weight of the boom and the associated parts in operative positions must be offset to prevent excessive burden on the hoisting machinery and consequent excessive cost in production and maintenance.

The counterweight system includes four weights 44, 45, 46 and 47 (Figs. 1, 7 and 9) connected in series by chains 48, the upper ends of which are secured to a beam 49 by clevises 50. The beam is supported by cables 51 running over drum surfaces 40 and 42 and made fast to them near their forward portions. At the lower ends the cables 51 are secured to an equalizer 52 which, in turn, is secured to a clevis 53 made fast to the beam 49.

The opposite ends of the chains 48 are secured to a beam 49a which, in turn, is made fast to the backhaul cables 33 by clevises 54. The cables 33 are looped over sheaves or pulleys 55, mounted on the top of the tower frame and beyond the pulleys the cables 33 are trained downwardly along the drum surfaces 40 and 42 between the cables 51 and made fast adjacent to the lower ends thereof.

The proportions between the counterweight system and the parts to be counterweighted, the number of weights, their spacing and length and proportions of the backhaul ropes or cables de-

pend somewhat on personal preference and judgment, and will be varied to meet particular conditions. In the installation above mentioned there are four weights of 25,000 pounds each. When the boom is in horizontal position the four weights are as indicated in Fig. 7, and for other positions thereof within the operating range they will be somewhat higher or lower, according to the position of the boom. In that particular design all of the weight is used as a counterbalance from a position 29½° above horizontal to a position 22° below horizontal. As the boom rises from 29½° above horizontal, first the weight 47, then the weight 46, then the weight 45, passes away from the right side of the loop formed by the chains 48 and the cables 33 (Figs. 1 and 7) and go up on the left side. As they do so they change their action from tending to raise the boom to tending to lower the boom. In the stowed position, shown in dotted lines in Fig. 1, something in excess of 75,000 pounds of the weights is acting to lower the boom and the pull on the hoisting rope, with maximum estimated wind, is about the same as when the boom is in the horizontal position. The loss or gain of a weight on one side of the system is completed in about 4½ feet of rope travel, or 14½° angular motion of the boom.

The distribution can be changed in proportion at any time by a minor shift in rope lengths or varying the amount of the individual weights.

The trolley carriage for the elevator leg

The elevator leg 10 is mounted on the horizontal shaft 15 by means of a ball and socket joint 60, which permits the leg to swing like a pendulum, also to have a limited torsional movement about the diameter of the ball.

The carriage for the shaft includes two trolley frames 61 (Figs. 10, 11 and 12), each of which has four flanged wheels 62, running on the bottom flanges 63 of a beam 64, secured to and suspended below the boom by brackets 65 and 66. Guide rollers 67 in the trolley frames run along the lower sides of the flanges 63 and steady the trolleys. The carriage is moved in and out along the beam 64 and held in various operative positions by screws 68, driven by a motor 69, through suitable gearing 70. Some will prefer to use an endless cable and drum in place of the screws and that sort of shifting mechanism will have advantages under some conditions.

The belt conveyors

The belt conveyors 24 and 25 on the boom and the belt conveyor 27 on the tower frame, each include a belt 71, supporting idlers 72, return rollers 73 and separate motor driving mechanism 74, all mounted on a suitable frame here shown, for simplicity, as forming housings 75, 76 and 77, for the respective conveyors.

The forward end of the frame 75 for the conveyor 24 is equipped with downwardly inclined arms 78, terminating in saddle shoes 79 (Figs. 11 and 12) resting upon and made fast to the shaft 15 at each side of the elevator leg 10. The opposite end of the conveyor frame 75 has supporting rollers 80 running on tracks within the housing frame 76 of the conveyor 25. By comparing Figs. 7, 8 and 13, it will be clear how the conveyor 24, with its housing, may move in and out with the trolley carriage and the elevator leg and telescope into and out of the housing frame 76 of the conveyor 25. Suitable weather strips 81 make a tight

seal between the conveyor housing frames 75 and 76.

The horn spout.

In order to provide continuous inclosure between the housing frame 16 of the conveyor 25 and the housing frame 17 of the conveyor 27, the former is provided with a spout 26 (Fig. 13) co-operating with a funnel 82 on the latter. The spout 26 is, in effect, a continuation of the housing frame 16 at the tail end of the conveyor belt 14, and includes a long curved wall 83, opposed to a generally flat wall 84, both leading to a discharge opening 85, which in all positions of the boom between 22° below horizontal and 25° above horizontal, communicates with the funnel 82, as will appear from Figs. 14 and 15. Beyond the wall 84 the wall 83 is continued at 86 to form a closing seal for the funnel 82.

The cooperating edges of the spout 26 and the funnel 82 are interlocked or overlapped to make weather-tight seal. For instance, as shown at 87 in Fig. 17. At the upper left of the funnel 82 in Fig. 13 there is a sloping wall 88 cooperating with the outer surface of the wall 83 and the joint is made weather-tight by suitable weather strips 89. The opposite wall of the funnel 82 is provided with a curved wall 90, cooperating with the wall 86 and the wall 83 to close the opening 85 when the boom is in extreme elevated positions, as shown in Fig. 16.

The marine leg 10 is entirely enclosed and with the telescoping chute 23, the housing frames for the conveyors and the cooperating spout and funnel, the entire path of the sugar from the ship to the conveyor 28, under the shed 29, is enclosed so as to protect it from contamination and the weather.

By applying the hoisting and counterweight forces to the drum surfaces on the boom, the use of a jib, and all of its attendant incidents, is eliminated with a great saving in head room. This appears very strikingly in the stowed position shown in dotted lines in Fig. 1.

We claim as our invention:

1. In a device of the class described, a supporting frame, a boom mounted on the frame to swing up and down through a vertical angle between an upper stowed position and lower operating positions, a carriage movable in and out along the boom, a marine leg mounted to swing from the carriage, and adjustable conveyor means mounted on the boom and comprising a section movable along the boom having one end connected to the carriage and a cooperating section mounted in fixed position on the boom and discharging at the frame.

2. In a device of the class described, a supporting frame, a boom mounted on the frame to swing up and down through a vertical angle between an upper stowed position and lower operating positions, a carriage movable in and out along the boom, a marine leg mounted to swing from the carriage and extending above same, adjustable conveyor means mounted on the boom and comprising a section movable along the boom having one end connected to the carriage and a cooperating section mounted in fixed position on the boom and discharging at the frame, and an automatically adjustable delivery connection between the upper end of the marine leg and the adjacent section of the conveyor means.

3. In a device of the class described, a supporting frame, a boom mounted on the frame to swing up and down through a vertical angle between

an upper stowed position and lower operating positions, an elongated conveyor extending lengthwise along the rear portion of the boom, a carriage movable in and out along the forward portion of the boom, a second elongated conveyor having its forward end connected to the carriage and having its rear end movable along the boom in overlapping relation to the first conveyor so as to discharge thereon, and a marine leg mounted to swing from the carriage and deliver to the first conveyor.

4. In a device of the class described, a supporting frame, a boom mounted on the frame to swing up and down through a vertical angle between an upper stowed position and lower operating positions, an elongated conveyor extending lengthwise along the rear portion of the boom, a carriage movable in and out along the forward portion of the boom, a second elongated conveyor having its forward end connected to the carriage and having its rear end movable along the boom in overlapping relation to the first conveyor so as to discharge thereon, a marine leg mounted to swing from the carriage and raise material to a point above the level thereof, and a collapsible chute for delivering material from said point to the second conveyor.

5. In a device of the class described, a supporting frame, a forked boom mounted on the frame to swing up and down through a vertical angle between an upper stowed position and lower operating positions, an elongated conveyor extending lengthwise along the rear portion of the boom, a carriage movable in and out along the forward portion of the boom and spanning the space between the forks thereof, a second elongated conveyor having its forward end connected to the carriage, and having its rear end movable along the boom in overlapping relation to the first conveyor so as to discharge thereon, and a marine leg mounted to swing from the carriage and deliver to the second conveyor.

6. In a device of the class described, a supporting frame, a boom mounted on the frame to swing up and down through a vertical angle between an upper stowed position and lower operating positions, a carriage movable in and out along the outer end portion of the boom, adjustable conveyor means mounted on the boom and comprising a section movable along the boom having one end connected to the carriage and a cooperating section mounted in fixed position on the boom and discharging at the frame, a marine leg mounted to swing from the carriage and delivering to the adjacent section of the conveyor means, and means including a cable connected directly to the boom for hoisting the boom to stowed position, said hoisting means being independent of the carriage whereby the carriage, the adjacent section of the conveyor means and the marine leg may be moved towards the inner end of the boom for storage.

7. In a device of the class described, a supporting frame, a boom mounted on the frame to swing up and down through a vertical angle between an upper stowed position and lower operating positions, said boom having a curved arm at its rear end portion, a carriage movable in and out along the outer end portion of the boom, a conveyor movable lengthwise along the boom and having its outer end connected to the carriage, a marine leg mounted to swing from the carriage and delivering to the conveyor, and means including a cable connected directly to the boom and trained around said curved arm and adapted

to be pulled for hoisting the boom to stowed position, said means being independent of the carriage whereby the carriage, conveyor and marine leg may be moved towards the inner end of the boom for storage.

8. In a device of the class described, a supporting frame, a boom mounted on the frame to swing up and down through a vertical angle between an upper stowed position and lower operating positions, a carriage movable in and out along the outer end portion of the boom, a marine leg mounted to swing from the carriage, adjustable conveyor means mounted on the boom and comprising a section movable along the boom having one end connected to the carriage and a cooperating section mounted in fixed position on the boom and discharging at the frame, and means including a cable connected directly to the boom and adapted to be pulled for hoisting the boom to stowed position, said means being independent of the carriage whereby the carriage and marine leg may be moved towards the inner end of the boom for storage with the boom in upper stowed position.

9. In a device of the class described, a supporting frame, a boom mounted on the frame to swing up and down through a vertical angle between an upper stowed position and lower operating positions, a carriage movable in and out along the boom, a marine leg mounted to swing from the carriage, adjustable conveyor means mounted on the boom and comprising a section movable along the boom having one end connected to the carriage and a cooperating section mounted in fixed position on the boom and discharging at the frame, and means operating on the boom, independent of the carriage, for raising and lowering the boom whereby the carriage and the marine leg may be moved toward the lower end of the boom and the boom held in elevated position for storage.

10. In a device of the class described, a sup-

porting frame, a boom fulcrumed on the frame and divided by the fulcrum into an inner operating arm and an outer load-carrying arm, a carriage movable in and out along the load-carrying arm, a marine leg mounted to swing from the carriage, conveyor means on the boom for receiving material from the marine leg, said means comprising a section movable along the boom having one end connected to the carriage and a cooperating section mounted in fixed position on the boom and discharging at the frame, and means operating directly on the operating arm, independent of the carriage, for raising and lowering the boom between lower operating positions and an upper stowed position with the carriage and the marine leg moved toward the fulcrum.

11. In a device of the class described, a supporting frame, a boom fulcrumed on the frame and divided by the fulcrum into an inner operating arm and an outer load-carrying arm comprising two members connected in side by side spaced relation adjacent to the fulcrum and unconnected at the outer end of said arm whereby said arm is of open-ended fork construction, a carriage movable in and out along the load-carrying arm, a marine leg mounted to swing from the carriage, between the forks, conveyor means on the boom for receiving material from the marine leg, said means comprising a section movable along the boom having one end connected to the carriage and a cooperating section mounted in fixed position on the boom and discharging at the frame, and means operating directly on the operating arm, independent of the carriage, for raising and lowering the boom through a vertical angle between lower operating positions with the carriage in adjusted position on the load-carrying arm and an upper stowed position with the carriage and the marine leg moved toward the fulcrum.

HOMER K. HERRICK.
CHARLES J. HORN.
